PULL TAB FOR A TEAR STRIP OPENER

Joseph P. Rodden, Montgomery, Pa., assignor to Crown Cork & Seal Company, Inc., Philadelphia, Pa., a corporation of New York

Filed Feb. 12, 1968, Ser. No. 10,528

Term of patent 14 years

Int. Cl. D9—02

U.S. Cl. D9—256

Fig. 1.

Fig. 2.

*Fig. 3.**Fig. 4.**Fig. 5.**Fig. 6.*FIGURE 1 is a perspective view of a pull tab for a tear strip opener showing my new design;

FIGURE 2 is a bottom plan view;

FIGURE 3 is a top plan view;

FIGURE 4 is a side elevational view;

FIGURE 5 is a sectional view taken along the line 5-5 of FIGURE 3; and

FIGURE 6 is an end elevational view looking from the right of FIGURE 4.

I claim:

The ornamental design for a pull tab for a tear strip opener, substantially as shown.
